UNITED STATES PATENT OFFICE.

WILLIAM L. BECTON, OF HALLS, TENNESSEE

BACKBAND BUCKLE.

Application filed June 9, 1923. Serial No. 644,434.

To all whom it may concern:

Be it known that I, WILLIAM L. BECTON, a citizen of the United States, residing at Halls, in the county of Lauderdale and State of Tennessee, have invented certain new and useful Improvements in Backband Buckles, of which the following is a specification.

This invention relates to improvement in buckles, and more particularly to an improved back band buckle.

The primary object of the invention is to provide a back band buckle for webbing bands for use on the standard sizes of back bands which are 4 and 5 inches in width.

Another object of the invention is to provide a back band buckle of this character which will be so constructed as to avoid tearing and ripping of the band, thus prolonging its life.

Other objects of the invention will appear upon consideration of the following detailed description and accompanying drawings, wherein:

- 25 Figure 1 is a plan view of the buckle in operative position,
- Figure 2 is an edge elevation of the same,
- Figure 3 is a longitudinal section,
- Fig. 4 is an edge elevation showing the 30 gripping element opened,
- Figure 5 is a cross section taken on the line 5—5 of Figure 4,
- Figure 6 is a plan view of the device swung to open position,
- 35 Figure 7 is a detailed view of a portion of the locking device, and
- Figure 8 is a plan view of the same.

Referring to the drawing by numerals, two gripping elements 1 and 2 are formed of corrugated plate having transverse corrugations which are adapted to fit together and have sufficient resiliency to include a spring action when the webbing is placed between them. The bottom plate 2, at one 45 end, is provided with ears 3 to receive the ends of a pin 4 which receives a sleeve 5 on the corresponding end of the complementary gripping plate 1, thus providing a pivotal connection between the two corrugated 50 gripping plates 1 and 2. The opposite end of the gripping plate 2 is hinged to the hook element 6 which forms one of the elements of the locking latch 7. This member 6 is provided with a tongue 8 at one end which 55 is received by the loop 9 of the other latch member 10 which is pivotally connected to

the end of the upper gripping member 1 as indicated at 11. The end of the member 10, at opposite edges thereof, has the tongues 12 projecting laterally and adapted to engage the locking hooks 13 which are formed on opposite edges of the lower gripping element 2 and so arranged as to permit the tongues 12 to move into and out of engagement with the hooks 13 as the member 10 is swung on its hinge, as shown to advantage in Figures 4 and 7 of the drawings.

When the device is in use, the webbing 14 will be passed into the space between the gripping elements, and threaded through the corrugations until the end 15 is extended out beyond the latch device as shown in Figure 3. When the webbing is thus threaded through the space while the parts are in open position as shown in Figure 4, the webbing will be engaged between the corrugations of the gripping plate. The latch elements will then be swung downwardly together until the hook 6 is engaged with the loop of the latch element, causing the tongue 12 to engage the hook 13, thus binding the two corrugated gripping plates together and firmly holding the webbing against slipping or disconnection. Obviously, the webbing will not be torn when a pull is exerted on it and the elimination of teeth will prolong the life of the webbing.

Minor changes may be made in the details of construction without departing from the spirit of the invention or the scope of the claims hereunto appended.

What I claim is:

1. In a device of the character described comprising complementary gripping plates pivotally connected together and adapted to overlap, the said plates being so corrugated, that the corrugations will fit together when the said plates are overlapped, latch members forming supporting means pivotally connected to the free ends of the plates and adapted to maintain the plates in closed relation when the latch members are in operative position, and a webbing adapted to be inserted in the space between the said corrugated binding plates.

2. In a device of the character described comprising a pair of complementary binding plates, each plate having transverse corrugations, the corrugations being adapted to register with each other when the plates are closed, the plates at one end being hinged together, a latch element including a sup

porting hook hinged to one plate, a loop hinged to the other plate, the said hook and loop being adapted to be engaged when the plates are closed, webbing adapted to be inserted in the space between the binding plates, one of the said plates having retaining hooks at opposite edges, the said loop element of the latch being provided with tongues adapted for engagement with said retaining hooks when the latch element is closed for holding the two binding plates in close relation to firmly bind the said webbing.

3. In a device of the character described comprising a pair of hinged plates adapted to move to open and closed relation, the said plates being transversely corrugated whereby the corrugations may register with each other when the plates are closed, one of the said plates being connected at its free end to a loop, a supporting hook hinged to the other plate at its free end and adapted for co-

operation with the same loop to maintain the said binding plates in closed position one of the said binding plates also having retaining hooks at its opposite marginal edges, tongues formed on the said loop element of the latch, and adapted to be out of engagement with said retaining hooks when the latch is open, the said tongues being adapted to move into engagement with said retaining hooks when the latch is closed whereby the said binding plates will be moved into close relation, and a strip of webbing adapted to be threaded through the space between the corrugations of the said binding plates.

In testimony whereof, I have affixed my signature in the presence of two witnesses.

WILLIAM L. BECTON.
